UNITED STATES PATENT OFFICE

157,556

WOMAN'S PLAY SUIT OR ARTICLE OF SIMILAR NATURE

Charles Ackerman, Madison County, Ohio

Application February 5, 1948, Serial No. 144,304

Term of patent 14 years

(Cl. D3—17)

To all whom it may concern:

Be it known that I, Charles Ackerman, a citizen of the United States of America, and a resident of the county of Madison, and State of Ohio, have invented a new, original, and ornamental Design for a Woman's Play Suit or Article of Similar Nature, of which the following is the specification, reference being had to the accompanying drawing, forming a part thereof:

Figure 1 is a front elevational view of a woman's play suit or article of similar nature, showing my new design.

I claim:

The ornamental design for a woman's play suit or article of similar nature, substantially as shown.

CHARLES ACKERMAN.
